UNITED STATES PATENT OFFICE

JOHANNES C. VAN BERKEL, OF COPENHAGEN, DENMARK, ASSIGNEE, BY MESNE ASSIGNMENTS, TO NAAMLOOZE VENNOOTSCHAP MAATSCHAPPIJ TOT VERAARDIGING VAN SNIJMACHINES VOLGENS VAN BERKEL'S PATENT EN VAN ANDERE WERKTUIGEN, OF ROTTERDAM, HOLLAND, OF ROTTERDAM, NETHERLANDS, A LIMITED-LIABILITY COMPANY

SLICE DEFLECTOR

Application filed January 20, 1927, Serial No. 162,228, and in Great Britain September 8, 1926.

This invention relates to machines for slicing meat and other material, and has for one of its objects the provision of means for clearing the slice as it is formed from the slicing 5 knife and directing the movement of the slice into a desired position.

Other objects will appear from the following description.

The invention is exemplified in the combination and arrangement of parts shown in the accompanying drawing and described in the following specification, and it is more particularly pointed out in the appended 10 claims.

15 In the drawing—

Fig. 1 is an elevation of a slicing machine having one embodiment of the present invention applied thereto;

20 Fig. 2 is a top plan view of the machine shown in Fig. 1, with parts in section; and

Fig. 3 is a fragmentary elevation at right angles to Fig. 1 showing the rotary knife and slice deflector.

25 At present various kinds of deflectors are used for deflecting the cut slices clear of the knife, but they have the disadvantage that the slices adhere to the deflecting face so that the movement of the slices away from the knife is frictionally retarded.

30 To avoid this disadvantage the slice deflector may be formed with ribs extending substantially horizontally across the deflecting face. With this formation the contact area of the deflecting face and the opposition 35 offered to movement of the slices are considerably reduced.

According to this invention, there is provided a slicing machine of the kind stated in 40 which the slices are pneumatically acted upon in order to prevent them adhering to the slice deflector. Preferably, the slices are acted upon by air under pressure, as they are being cut, so as to prevent adherence as aforesaid 45 and also to cause them to be blown from the deflecting face at a part thereof adjacent to the cutting edge of the knife. The air may be directed through holes in the slice deflector onto the slices and may be supplied from a pumping device operated by the machine or 50 from a vessel containing compressed air.

Means may be provided for regulating the supply of air to the deflector.

The slicing machine shown comprises a rotary knife 1 journaled in a bracket 2, a reciprocating carriage 3 slidably mounted on guides 4, a hand wheel 5 by means of which the machine is operated in the usual manner and a bed plate 6, serving as a support for the working parts.

Fitted to the bracket 2 is a slice deflector 7 which is inclined to the knife in such a manner as to cause the slices, as they are cut, to turn over and fall upon a receiving table 8.

The deflector 7 is connected to a stationary air pump cylinder 11 by way of a pipe 10 fitted with a valve 14, the piston 12 of the air pump being secured by means of a piston rod 16 to the carriage 3. The piston 12 is provided with a port therethrough and co-operating with which port is a spring flap 15 constituting a non-return valve. The deflector 7 is shown formed with ribs on its deflecting face and with a plurality of holes 13 through this face.

During the cutting stroke of the carriage 3, air is forced by the air pump through the pipe 10 to a substantially closed space between the deflector 7 and the knife 1. The air issues from the holes 13 and forces away from the deflecting face of the deflector the slice being cut.

The pressure of the air can be regulated by means of the valve 14.

The holes may be so inclined and dimensioned as to distribute the air over the slices in a manner which will insure that the slices are deposited properly on the receiving table.

The means described is chosen merely by way of example and many modifications may be adopted without departing from the spirit of the invention. For example, the slice deflector may be formed hollow so as to afford a chamber into which the air under pressure may be led. Further, instead of an air pump, a vessel containing compressed air may be used. The means is applicable to slicing machines other than those of the reciprocating carriage type, as will be readily understood. Further, the slice deflector illustrated has a

ribbed deflecting face, but any suitable kind of deflector may be used.

I claim:

1. The combination with a slicing knife, of a slice deflector disposed adjacent the cutting edge of said knife at one side thereof, for deflecting slices away from said knife, and means for supplying air to the face of said deflector adjacent the slice formed by said knife to reduce the resistance offered by said deflector to the movement of the slice thereover.
2. The combination with a rotary slicing knife, of a slice deflector disposed adjacent the cutting edge of said knife at one side thereof in position to direct slices away from said knife as they are severed, said slice deflector having a plurality of discharge openings distributed over the face thereof, and means for discharging air from said openings.
3. The combination with a slicing knife, of a slice deflector disposed at one side of said knife for directing the slices away from said knife, said slice deflector having projections on the face thereof to limit the contact between said deflector and slices formed by said knife, and means for discharging air from the face of said deflector.
4. The combination with a slicing knife, of a deflector disposed adjacent one side thereof for directing slices away from said knife, said deflector having projections on the face thereof with depressions between said projections, and means for injecting air into said depressions.
5. The combination with a slicing knife, of a deflector disposed adjacent one face of said knife, said deflector having ribs thereon with intervening depressions, and means for discharging air into said depressions to prevent slices from adhering to said deflector.
6. The combination with a slicing knife, of a support for receiving slices formed by said knife, a slice deflector disposed adjacent one face of said knife, said slice deflector having a plurality of discharge openings distributed over the face thereof, and means for discharging currents of air from said openings to direct a slice from said slice deflector onto said support.
7. The combination with a slicing knife, of a deflector disposed adjacent the cutting edge of said knife at one side thereof to deflect slices away from said knife, said deflector having a plurality of perforations therein, means for discharging air currents through said perforations to reduce the friction between said deflector and the slices moving thereover, and means for controlling the force of said currents.
8. The combination with a slicing machine having a slicing knife, of a slice deflector for directing slices away from said knife, an air compressor operated by said slicing machine,

and means for conducting air from said compressor to the surface of said slice deflector to prevent curling of the slices as said slices pass over said deflector.

9. The combination with a slicing machine having a slicing knife, of a slice deflector for directing slices away from said knife, an air compressor operated by said slicing machine, a conduit for conducting air from said air compressor to said slice deflector, said slice deflector having perforations for directing air against the slices formed by said knife, and a valve for controlling the passage of air from said air compressor to said slice deflector.

10. A slice deflector for slicing machines comprising a member arranged to deflect slices away from the cutting edge of a slicing machine knife, and supplemental means for reducing the resistance offered by said deflector to the passage of slices thereover comprising pneumatic means for acting on said slices in a direction toward the slices as the latter move over said slice deflector.

11. A slicing machine comprising a slicing knife, a slice deflector adjacent said knife, projections on said deflector adapted to contact with a slice cut by said slicing knife to thereby reduce the resistance offered by said deflector to the movement of said slice thereover, openings in said deflector, and means for directing air out of said openings against said slice as it moves over said deflector.

12. A slice deflector for deflecting slices away from the knife of a slicing machine comprising a member having a chamber therein, a slice deflecting surface on said member, said member having openings therein forming communicating means between said chamber and said surface, and means for introducing air under pressure to said chamber.

13. A slicing machine comprising a slicing knife, a substance support, means for moving said substance support relatively to said knife so that said knife will cut slices from the substance on said support, means for deflecting slices away from said knife by a current of air as said slices are formed, and means for regulating the force of said current of air.

14. In a slicing machine, the combination with a slicing knife, of a substance support movable relative thereto, a slice deflector adjacent said substance support, an air compressor operated by the relative movement between said slicing knife and support, and means for directing air compressed by said compressor between the surface of said deflector and a slice moving thereover, said compressor being operable as said support moves toward said slicing knife.

15. In a slicing machine, the combination with a slicing knife, of a support movable relative to said knife, said slicing knife

- being adapted to cut successive slices from a substance of substantial thickness mounted on said support, said slices tending to move over the edge of said knife and cling to the 5 side of said knife during the slicing operation, and means for injecting air between the flat sides of said slice which lies adjacent said knife and the side of said knife to prevent said slice from clinging to the side of 10 said knife and for the purpose of assisting the depositing of said slice on a support and for reducing the resistance offered to the rotation of the knife by the engagement of the slice with the side thereof.
- 15 16. The combination with a slicing knife, of a slice deflector arranged adjacent said knife, and means for supplying air to said deflector, said deflector having a discharge opening therein for directing air therefrom 20 against the broad side of a slice formed by said knife and between said broad side of said slice and said deflector over a substantial area of said deflector to thereby reduce the resistance offered by the deflector to the 25 movement of said slice thereover.
17. In a slicing machine, the combination with a rotary knife, of a slice deflector disposed adjacent the cutting edge of said knife at one side thereof for directing slices away 30 from said knife as they are formed thereby, and means for injecting air between substantial areas of said slice deflector and the slice being formed to prevent distortion of said slice as said slice moves over said deflector 35 by reducing the resistance offered by said deflector to the movement of the slice thereover.
18. In a slicing machine, the combination with a rotary knife, of a slice deflector disposed adjacent the cutting edge of said knife at one side thereof and in substantially fixed position with respect to said knife, said deflector having an opening in the surface thereof, and means for discharging air 40 through said opening against the slice as the latter passes over said deflector and over a substantial portion of the opposed surfaces of said deflector and said slice to thereby reduce the resistance offered to the movement of 45 the slice over the surface of the deflector.
19. The combination with a slicing knife, of a support for receiving slices severed by said knife, and means for directing a plurality of distributed streams of air against the 50 face of said slice as it is severed to thereby direct said slice broad side down onto said support, said knife being adapted to cut slices from a substance of substantial thickness so that normally a considerable portion 55 of said slice comes into engagement with said knife and tends to be carried in the direction of movement of said knife, said distributed streams of air being directed against the side of said slice adjacent said knife to deflect said 60 slice out of engagement with the side of said 65
- knife and thereby reduce the tendency of said slice to move with said knife and assist in depositing said slice broad side down on said support. 70
20. The combination with a slicing machine having a slicing knife, of a slice deflector for directing slices away from said knife as they are severed thereby, and means operated by said slicing machine for directing a current of air between a substantial portion of said deflector and the broad side of said slices severed by said knife to thereby reduce the resistance offered by said deflector to the movement of the slices thereover. 75
21. A slicing machine comprising a slicing knife, of a means for discharging a plurality of distributed air currents against the broad face of a slice as it is formed, said broad face being that face which lies on one side of the cut taken by said slicing knife and which tends to move over the surface of said knife adjacent the edge thereof during the severance of the slice from the substance, said air currents moving the surfaces of said knife and slice which normally tend to engage each other, out of engagement with each other during the cutting of the slice to thereby prevent said slice from being carried along by said knife and the slice from retarding the 80 movement of said knife. 85
22. The combination with a slicing machine, of a slicing knife, an air compressing device operated by said slicing machine for directing an air current against the broad side of the slice which lies on one side of the cut made by said knife to thereby move said broad side of said slice out of contact with the adjacent side of said knife to thereby reduce the resistance which is offered to the 90 movement of said knife by the engagement which normally occurs between said knife and the slice. 95
- In testimony whereof I have signed my name to this specification on this 27th day of December A. D. 1926. 100
